UNITED STATES PATENT OFFICE.

FELIX KÄPPLER, OF DRESDEN, GERMANY, ASSIGNOR OF ONE-HALF TO HELEN FRASER, OF LONDON, ENGLAND.

MATCH RECEPTACLE.

Application filed January 21, 1928, Serial No. 248,525, and in Germany February 21, 1927.

This invention relates to a receptacle intended to receive and to store until use superposed match-plates or -disks consisting each of a large plurality of matches of paper, paste-board, wood or the like, which extend to several or all directions from a common centre which is the centre of the respective plate or disk. These latter may be circular or polygonal, and each plate or disk may be composed of a plurality of parts, say three or four or five etc., according to the polygonality, arranged around a common centre, but generally every one of the superposed layers is to consist of one plate or disk which is subdivided into match-forming portions by radial or nearly radially directed slits, these portions or matches being, thus, connected with each other only at their feet by the centre portion of the respective plate or disk.

The matches can be removed singly from the receptacle through a suitably located and shaped orifice generally provided with a cover. The superposed match-plates or -disks can be turned on a common axle properly held in or carried by said receptacle or by the receptacle and a base member or back member; as the case may be and as is more fully described hereinafter. The matches pertaining to, or forming, a plate or disk become successively visible in said orifice, and the plate or disk is manually turned in correspondence with the removal of the individual matches through the said orifice.

The receptacle covering and enclosing the superposed match-plates or -disks is generally bottomless, the bottom being a separate member, i. e. a base-plate or wall-plate, according as to whether the complete implement is to stand on a table or to be suspended from a wall. In the first case the implement is movable, in the other case stationary. In either case removing the matches singly by tearing each off the common centre portion of the plate or disk can be effected very conveniently and quickly, and also removing the finally remaining centre portions and inserting a fresh set of match plates or disks into the receptacle can be effected in a few seconds, as will also appear more fully by what follows.

The invention is illustrated diagrammatically and by way of examples on the accompanying drawing on which Figure 1 is chiefly a vertical section through and partly a side-view of, a filled match receptacle designed ac-

cording to this invention and intended for use on a table, Figure 2 a perspective representation of another constructional form intended to be suspended from a wall, Figure 3 a perspective representation of a combined match receptacle and ash-tray, and Figure 4 is a perspective representation of a combined match receptacle and a candlestick and Figure 5 is a perspective representation of a match receptacle combined with a flag.

Referring to Fig. 1, 1 denotes a base-plate, 4 a set of superposed match-plates or disks, 6 a cap-shaped cover forming a match receptacle which encloses said set and rests upon said base-plate. The centre portions of the 70 match-plates or -disks are perforated and through the superposed perforations extends a stationary axle 7, the lower end of which is provided with a removable nut 8 located in the concavo-convex central portion of said base-plate. 6^a is a partly horizontal and partly vertical recess through which the access to the match-plates or -disks, i. e. to the matches, is afforded. First the matches of the uppermost plate or disk 4 are used up, then those of the next plate or disk 4, and so on. When the matches of all plates or disks 4 have been used up, the nut 8 is unscrewed, the cover 6 with the axle 7 withdrawn, the remaining centre portions of the former set 80 4 removed, a fresh set inserted, and the filled cover again connected with the base-plate by means of the nut 8.

The recess 6^a can be closed by means of a flap 9, the shape of which corresponds to the shape of the recess 6^a. The flap 9 is hinged to the cover 6, and on it is an exchangeable piece of a rubbing foil covered with a mass on which the heads of the matches can be ignited, as usual.

It is assumed in Fig. 1 that the cover 6 is circular, but it may as well be polygonal, for instance octagonal as in Figs. 2-4, or hexagonal etc., just as desired. The flap may be self-closing either under its dead weight or by means of a suitably arranged spring. 5 in Fig. 1 denotes a cap covering the end of the axle projecting above the cover 6.

In the constructional form shown in Fig. 2 the match cover 6 is attached to a vertical wall-board 1^a bearing also a sheet-calendar 2. The cover 6 is attached to the wall-board in quite the same manner as the cover of Fig. 1 is attached to the base member 1. The recess through which the matches are to be taken

from the match receptacle is shown closed by the flap, and on this latter is a small frame 9^a holding the rubbing foil 9^b which can be exchanged after having been used up.

5 In Fig. 3 the match-receptacle is attached in horizontal position to an ash-tray 1^a, and in Fig. 4 it is combined with a candlestick 3, for which may be substituted, however, any other object, for instance a flag or an emblem 10 (Fig. 5) or a card with statements of any kind. The base-plate 1^c is in this instance also octagonal, like the cover 6, and this latter is placed upon said plate in such a position that the angles of the polygons follow one another in staggered arrangements.

15 The axle or bolt 7 may be connected with the receptacle by any desired means or in any desired manner, for instance by riveting or welding or soldering etc. I wish it to be understood that there may be departures from the details shown and described without departing from the essential contents of the invention. The constructional forms show merely a few examples. A great variety of other constructional forms is obviously possible.

I claim:

1. A match-receptacle, comprising, in combination, a plurality of superposed match plates consisting each of a plurality of matches integrally connected with each other at their feet, a cover enclosing said match-plates and having an aperture affording access to the matches, means for closing said aperture, and a base member to which said cover is detachably attached.

2. A match-receptacle, comprising, in combination, a plurality of superposed match-disks having each a hole in its centre portion and consisting each of a plurality of matches integrally connected with each

other at their feet in the centre portion of the disk, a cover enclosing said match-disks and having an aperture affording access to the matches, means for closing said aperture, a base member to which said cover is detachably attached, and a centrally located bolt by the intermediary of which the cover is connected with said base member and which serves as an axle for the said disks.

3. A match-receptacle, comprising, in combination, a plurality of superposed match-plates, consisting each of a plurality of matches integrally connected with each other at their feet, a cap-shaped cover which is open at its top and has in a portion of its top and in an adjacent portion of its rim a recess of a size permitting access to the matches in said cover, a correspondingly angular lid hinged to said cover, and a base member to which the said cover is detachably attached.

4. A match-receptacle, comprising, in combination, a plurality of superposed match-plates, consisting each of a plurality of matches integrally connected with each other at their feet, a cover enclosing said match-plates and having an aperture affording access to the matches, means for closing said aperture, a base member to which said cover is detachably attached and which is concavo-convex below the centre of the cover, a bolt extending from the centre of the top portion through the centres of the match-plates into the cavity below said concavo-convex base portion, and a nut screwed upon the lower end of said bolt and being located in said cavity.

In testimony whereof I affix my signature.

FELIX KÄPPLER.
